CLAIM

The ornamental design for a tire indicator, as shown and described.

DESCRIPTION

FIG. 1 is a perspective view of a tire indicator in a fully inflated tire with proper pressure showing my new design; FIG. 2 is a front view thereof; The back view is the same as the front view; The side view is flat and plain; FIG. 3 is a perspective view thereof in a partially deflated tire with inadequate pressure; and, FIG. 4 is a front view thereof.
